UNITED STATES PATENT OFFICE.

LOUIS BAUDENDISTEL, OF PERRYVILLE, MISSOURI.

HULLER.

1,320,968.

Specification of Letters Patent.

Patented Nov. 4, 1919.

Application filed April 11, 1919. Serial No. 289,365.

To all whom it may concern:

Be it known that I, LOUIS BAUDENDISTEL, residing at Perryville, in the county of Perry and State of Missouri, have invented 5 new and useful Improvements in Hullers, of which the following is a specification.

My present invention has to do with hulling apparatus and has for one of its objects the provision in a hulling apparatus of 10 a cylinder and concave constructed with a view to breaking and removing the hulls of walnuts.

Another object of the invention is the provision in a hulling apparatus of means for 15 separating the hulls and nuts and conducting the same separably out of the apparatus.

Other objects and advantages of the invention will be fully understood from the following description and claim when the same 20 are read in connection with the drawings accompanying and forming part of this specification, in which—

Figure 1 is a longitudinal vertical section of the hulling apparatus constituting the 25 best practical embodiment of my invention of which I am cognizant.

Fig. 2 is a side elevation of the same.

Fig. 3 is a detail section on an enlarged 30 scale illustrative of the arrangement of the hammer members and their appurtenances relative to the perimeter of the cylinder.

Fig. 4 is a detail plan showing the arrangement of the teeth on the concave.

Similar numerals of reference designate 35 corresponding parts in all the views of the drawings.

Among other elements my novel hulling apparatus comprises a main frame, 1, which is preferably, though not necessarily, of 40 wood, and may be of any construction compatible with the purposes of the invention.

Suitably fixed in the frame 1, is a concave 2 on which are teeth 3 arranged as illustrated and designed to afford abutments 45 against which the nuts may be forced with a view to expediting the thorough removal of the hulls.

Leading to the said concave at the upper and outer end thereof is a feed trough 4 which may be of the construction shown or of 50 any other construction without affecting my invention.

Mounted in suitable bearings above the concave 2 is the shaft 5 of the hulling cylinder 6. The said cylinder 6 is provided on its perimeter with flap-like hammers 7. These

hammers 7 are preferably though not necessarily arranged in staggered relation on the cylinder, and each is connected at 8 in a hinged manner to the cylinder. 60

It will also be observed that each hammer 7 is provided with a rod 9, arranged to extend loosely through an aperture in the cylinder wall and terminating within the cylinder in an enlargement 10; the purpose 65 of said enlargement being to bring up against the cylinder wall when the hammer is thrown outwardly by centrifugal force and thereby limit the outward movement of the hammer. Manifestly, while I prefer to arrange the hammers 7 in staggered relation as stated, I do not desire to be understood as confining myself to the same, inasmuch as other arrangements of the hammers may be resorted to without involving departure from 75 the scope of my appended claim. Springs 9^a on rods 9 cushion the hammers 7.

Mounted to swing in a general longitudinal direction in the frame 1 and in front of the cylinder and concave is a shaking 80 screen 11. The said screen is suspended on hangers 12 in the frame and is made up of rear and forward serrated portions 13 and a foraminous portion 14 disposed intermediate the portions 13. At its rear or inner 85 end the screen 11 is provided with an upwardly extending flange 15 designed and adapted to assure the nuts and hulls passing from the inner and forward end of the concave to the rear and inner end of the screen. 90

Disposed in the frame and below the inner serrated portion 13 of the screen is a fan casing 16 in which is a rotary fan 17, and leading downwardly and forwardly from said casing is a chute 18 which terminates at its 95 forward end in a transversely disposed trough 19 the point of discharge of which is at one side of the frame. It will be readily noticed that the foraminous portion 14 of the screen 11 is disposed above the chute 18. 100

Journalized at 20 in the frame is a transverse shaft bearing a crank 21. The said crank 21 is connected through a pitman 22 with the rear and inner end of the screen 11 whereby rotation of shaft 20 will be attended by longitudinal reciprocation of the screen 11. 105

The cylinder shaft 5 is connected through gear 23 with the crank shaft 20, and it is manifest that the said shaft 5 may be manually rotated or may be rotated from any suitable motor not illustrated. 110

In the practical operation of my apparatus the cylinder 6 is rotated in the direction indicated by arrow in Fig. 1, and incidental to said rotation the nuts to be hulled 5 are fed through the trough 4 to a position between the cylinder and its complementary concave. As the cylinder is rotated in the direction indicated the hammers 7 are thrown outwardly and serve to strike the 10 nuts against the teeth 3 of the concave with the result that the hulls are knocked off of the nuts. Subsequently to the breaking and removal of the hulls the nuts and hulls together are moved through the medium of the 15 hammers 7 up the forward and inner portion of the concave and will be discharged upon the inner serrated portion 13 of the screen 11. This screen 11, being reciprocated serves to feed both nuts and hulls toward the discharge end of the machine, and when the nuts reach the foraminations 14 they drop through to the chute 18 and pass upon the chute to the trough 19 by which they are conducted out of the machine. In- 20 cidental to the passage of the hulls and nuts over the trunk of the fan casing 16 the blast of air afforded by the fan serves to free the nuts of dust and dirt so that they are in a clean and wholesome state when received on 25 the chute 18. The hulls and other debris are carried out of the machine and discharged into a receptacle placed to receive them, or if preferred the discharge may be into the fan casing 23 of a pneumatic stacker as illus- 30 trated.

In serving to move the nuts and hulls upwardly and forwardly on the inner and forward portion of the concave the hammers 7 are adapted to move inwardly toward the periphery of the cylinder 6 with the result 40 that there is little or no liability of the apparatus being choked at that point.

It will be gathered from the foregoing that my novel apparatus is simple and compact in construction, and is adapted to expeditiously and thoroughly free the nuts from the hulls, and this without injury to the nuts and without liability of the nuts being scratched or otherwise marred. It 45 will also be gathered that the apparatus is well adapted to withstand the rough usage 50 to which apparatus of corresponding character is ordinarily subjected.

Having described my invention, what I claim and desire to secure by Letters-Patent 55 is:

In a hulling apparatus, the combination with a concave having teeth with flat sides, arranged in stepped formation thereon, of a cylinder spaced from the concave, flap-like 60 hammers hinged to the perimeter of the cylinder and having flat heads opposed to the flat sides of the teeth and also having arcuate rods movable in apertures in the cylinder wall and provided at the inner side thereof 65 with enlargements, and coiled springs on said rods and arranged between the cylinder and the hammers.

In testimony whereof I affix my signature.
LOUIS BAUDENDISTEL.
